(57) **CLAIM**

The ornamental design for a tubular container, as shown and described.

DESCRIPTION

FIG. 1 is a left side elevational view of a first embodiment of a tubular container showing our new design;

FIG. 2 is a back side elevational view thereof;

FIG. 3 is a front side elevational view thereof;

FIG. 4 is a top and left side perspective view thereof;

FIG. 5 is a top plan view thereof;

FIG. 6 is a bottom plan view thereof;

FIG. 7 is a left side elevational view of a second embodiment of a tubular container showing our new design;

FIG. 8 is a back side elevational view thereof;

FIG. 9 is a front side elevational view thereof;

FIG. 10 is a top and left side perspective view thereof;

FIG. 11 is a top plan view thereof; and,

FIG. 12 is a bottom plan view thereof.

The broken lines in the figures show boundaries of the invention and form no part of the claimed design.
